UNITED STATES PATENT OFFICE

137,060

DESIGN FOR A SAW

Olaf Lodeen, Hoquiam, Wash.

Application June 2, 1943, Serial No. 110,343

Term of patent 14 years

To all whom it may concern:

Be it known that I, Olaf Lodeen, a citizen of the United States, residing at Hoquiam, in the county of Grays Harbor and State of Washington, have invented a new, original, and ornamental Design for a Saw, of which the following is a specification, reference being had to the accompanying drawing, forming part thereof.

Figure 1 is a side elevational view of a saw showing my new design, the blade being shown

fragmentarily for convenience of illustration, and

Figure 2 is a top plan view thereof.

The essential feature of my design resides in the configuration of the handle shown in full lines.

I claim:

The ornamental design for a saw, as shown and described.

OLAF LODDEEN.
